UNITED STATES PATENT OFFICE.

LAWRENCE WESLEY HORNE AND WARREN NOBLE CRANE, OF NEW YORK, N. Y.

AUTOMATIC DEVICE FOR CONTROLLING THE SPEED OF TRAINS.

1,164,284.

Specification of Letters Patent. Patented Dec. 14, 1915.

Application filed September 4, 1913. Serial No. 788,073.

To all whom it may concern:

Be it known that we, LAWRENCE WESLEY HORNE, a citizen of the United States, and resident of the borough of Brooklyn, county of Kings, city and State of New York, and WARREN NOBLE CRANE, a citizen of the United States, and resident of the borough of Manhattan, city, county, and State of New York, have invented certain new and useful Improvements in Automatic Devices for Controlling the Speed of Trains, of which the following is a specification.

This device and invention relates to that portion of a train speed controlling apparatus, that shall remain a part of and permanently secured to the rails and road-bed.

In an application filed by us and bearing date of Sept. 4th 1913, Serial No. 788,077, we have fully set forth the train speed controlling mechanisms that shall be carried by the locomotive, and any reference thereto in this application is merely for the purpose of a more complete understanding of the whole invention, its operation, functions, and advantages.

This application will describe the electrical track circuits and all changes that may be necessary or desirable in the construction of the rails as well as certain mechanical and electrical appliances, that we have found expedient to attach to certain rails to accomplish certain useful results.

The following is what we consider the best means of carrying out this invention and the accompanying drawings form a part of this specification, in which:

Figure 1, is a diagram of a simple track circuit. Fig. 2 shows on a large scale, a short section of dia-magnetic rail, provided with an electro-magnetic device. Fig. 3, is a section through a rail and approximately on the line 4 in Fig. 3. This figure shows in elevation partly in section, the means for completing a magnetic circuit in a dia-magnetic section.

Similar reference numerals indicate like parts in all the figures where they appear.

In our device we utilize an inverted U shape magnet as indicated at 2. This magnet is supported upon a stem 3, and is carried by a locomotive or train and in such a position that it will be suspended over one of the running rails and sufficiently close thereto to be held downward to its fullest extent by the influence of the magnet upon the rail. In this invention, we utilize ordinary steel rails in that portion of the track where we desire the magnet should be retained down, but as our device in its operation requires that the magnetic circuit should be broken, so that the magnet may be more or less readily lifted, we interpose at predetermined points, sections of dia-magnetic or non-magnetic rail. The dia-magnetic rails may be similar to the ordinary steel rail; with the exception that they contain certain proportions of non-magnetic metals, so as to make the section that they span non-attractive to the magnet U. In our experiments, we have used a manganese rail for the dia-magnetic section. Although we see no reason why any non-magnetic rail of sufficient strength should not be used.

At 4, in Fig. 1, we show an ordinary steel rail and at 5, 6, 7, and 8, we show short lengths or sections of manganese rail. At 9, a track battery is arranged between two of the steel rails, and at 10, we show a feeder wire or electrical connection between one side of the track battery or rail connected therewith, and this feeder wire is by means of the short connections 11 secured to certain electromagnets arranged in operable relation with the manganese sections. To complete the circuit, the magnets of each manganese section are electrically secured to the opposite rail 16, which may be an ordinary steel rail.

As intimated, it is desirable that the manganese sections should under certain conditions attract or be attracted by, the magnet, and to obtain this desirable result, we show in Fig. 2, and on a larger scale a portion of the section 5. We have arranged soft iron plates or combs 12 and 13, one upon each side of the dia-magnetic rail taking care that the teeth of one of the combs, will be shortened or arranged in some other manner so that they will not interfere with the flange of a wheel running upon the rail. These plates or combs 12 and 13, are secured one to each end of a coil 14, and when the coil 14 is energized the plates 12 and 13 become the poles of a very efficient electromagnet. We have considered it advisable, to place a number of these coils adjacent to each dia-magnetic rail so as to assure the maintaining of an efficient magnetic circuit in the proximity of a dia-magnetic rail when it is required.

It will be readily understood that when the rails 15 and 16, to which the battery 9 is

electrically secured, are short circuited, no current will pass through the coils 14. Therefore a train or locomotive carrying a magnet 2, will have its magnet held down, 5 while passing over an ordinary steel rail. Upon approaching a manganese or dia-magnetic section, which is temporarily out of circuit with the battery 9, the magnet 2 may be lifted by any desirable means, but when 10 another section of steel rail is reached, the magnet will again be attractive and held down until another dia-magnetic section, again interrupts the magnetic circuit. When however the battery 9 is not short circuited, 15 its current will be free to pass through the coils 14, energizing the plates or combs 12 and 13, holding the magnet down, even when passing an otherwise dia-magnetic section.

It will be noted that the dia-magnetic sections 5 and 6 which we may sometimes refer to as the distant signal sections are at a greater distance from each other, than are the sections 7 and 8, which constitute what we may sometimes term the home-signal sections. This is desirable for it is by this means that we obtain speed control. When the section of a road immediately ahead of the one approached by a train is occupied by another train or by any other device 25 that will short circuit the battery 9 contained therein, we desire that the rearmost train shall have its speed reduced and shall be stopped before it can enter the section or block occupied by another train. Should 30 the engineer or operator fail to observe the signals usually displayed, our device will control the speed of the train. It will not be found desirable to immediately stop the train, but its speed should be reduced within 35 certain safe limits, and as we have arranged that it will require more than one interruption of the magnetic circuit to stop a train, and as we have arranged so that a series of such interruptions occurring at certain intervals, will have no effect upon a train, we space 40 the distance signal dia-magnetic section sufficiently far apart so that they will not effect the train unless it be traveling at a high rate of speed. We gradually shorten the 45 distance between the dia-magnetic sections making those at the home signal so short, that a train cannot pass them even at a particularly low speed while the block ahead is occupied by a train. Here we have shown 50 but two series of dia-magnetic sections forming the distant and home signal, but we desire it understood that we may use one or more series of dia-magnetic sections either stopping the train immediately that a 55 energized dia-magnetic section is reached, or by the use of a number of sections spaced varying distances apart, continually reduce the speed of the train until the last section 60 is reached, which will completely stop the 65 train. It will be understood that when the

block immediately ahead of a train is not occupied, the dia-magnetic sections will be magnetic by the completion of the battery circuit through the electro-magnets 14, and the speed of the running train will not be 70 affected.

It is obvious that modifications may be made within the scope of the appended claims without departing from the principle or sacrificing the advantages of this invention. We may employ a greater or fewer number of magnet coils than here shown or we may increase or decrease the capacity of each coil. For the sake of convenience, we have shown a closed circuit 80 battery between the rails of a block section, but we desire it to be understood that a relay or other device conforming to standard signal practice may be used to open the circuit and that the energy furnished to the 85 electromagnets contained in a dia-magnetic section may be supplied by means of a line wire connected to any source of electric power.

Although we have shown a comb 4, and a 90 plurality of electromagnets for establishing a magnetic circuit adjacent to the dia-magnetic or non-magnetic rail sections, we desire it understood that any other method for establishing this magnetic circuit may be 95 utilized.

Having carefully and fully described our invention what we claim and desire to secure by Letters Patent is:—

1. A device for controlling the speed of 100 trains which consists of a track comprising magnetic and dia-magnetic rails and stationary means for establishing a magnetic field adjacent to said dia-magnetic rail for the purpose set forth.

2. A device of the character described having a non-magnetic rail, a plurality of magnet coils arranged adjacent thereto, and means for establishing and interrupting a circuit through said coils for the purpose 110 set forth.

3. A device of the character described having ordinary rails, dia-magnetic rails interposed, and spaced apart and means for completing a magnetic field around said 115 dia-magnetic rails for the purpose set forth.

4. A device of the character described having in combination with a track divided into sections, non-magnetic rails inserted in one said section, magnetic devices arranged 120 adjacent to said non-magnetic rails, and a source of current supply, said magnetic devices and current supply being in closed circuit with a second section, said magnetic devices being adapted to be deenergized by 125 the short circuiting of the said second section for the purpose set forth.

5. A device of the character described comprising a track, having magnetic and non-magnetic sections, magnet coils ar- 130

ranged adjacent to said non-magnetic sections, plates extending upward from said coils, and adapted to be included in the magnetic field thereof, and a depending 5 magnetic member arranged to be operated upon by said magnetic and non-magnetic sections in combination with electrical means for energizing said coils when desired.

6. A device for controlling the speed of 0. trains having in combination with a magnet, a track having magnetic sections, and dia-magnetic sections interposed at predetermined distances apart, said dia-magnetic

sections being arranged in pairs, the spacing between each pair being shorter or longer 15 than that of other pairs as herein specified and for the purpose set forth.

Signed at the city of New York, county of New York, and State of New York this 29th day of August 1913.

LAWRENCE WESLEY HORNE.
WARREN NOBLE CRANE.
